UNITED STATES PATENT OFFICE

HERBERT F. WALKER, OF ROCHESTER, NEW YORK, ASSIGNOR TO SARGENT & GREEN-LEAF, INC., OF ROCHESTER, NEW YORK, A CORPORATION OF NEW YORK

LOCKING MECHANISM

Application filed July 17, 1925, Serial No. 44,373. Renewed April 19, 1926.

The present invention relates to locking mechanisms for guarding the doors of safes, vaults or the closures of other compartments used for protecting valuables of different kinds. One object of the invention is to provide improved locking mechanism for such doors or closures including a combination or other suitable lock and a variable time-mechanism adapted to normally prevent the release of obstructing means for holding in check the securing parts of the door, but which is so controlled as not to function until said lock has been released or unlocked, whereby to foil any attempt on the part of unauthorized persons to gain access to the safe or vault at a given time by the use of a key or by forcing one having the combination to disclose the same or by successfully operating the combination through their own efforts.

Another object is to so construct a time mechanism and a combination lock for use with the doors of safes, vaults and other compartments as to render the combination lock effective to automatically move an obstructive element into position to prevent release of the bolt-work for securing the door upon locking the latter and destroying the combination and to so arrange the time-mechanism as to effect release of said element at any predetermined time desired.

A further object of the invention is to provide for use in connection with vault doors and other forms of closures a combination lock and time-mechanism so arranged that a suitable device for guarding the bolt-work of the door will be moved to operating position by the combination lock upon destroying the combination and in which the time-mechanism can be set to operate for any predetermined period desired, but which will not function until the combination lock has been unlocked, thereby delaying the opening of the door for as long a period as desired after operation of the combination.

A further object of the invention is to provide a combination lock and time-mechanism in which the former is adapted to control means by which the time-mechanism is normally prevented from operating and also by

which an obstructive element is moved, upon destroying the combination, which will prevent withdrawal of the bolt-work for locking the door.

To these and other ends the invention resides in certain improvements and combinations of parts, all as will be hereinafter more fully described, the novel features being pointed out in the claims at the end of the specification.

In the drawings:—

Figure 1 is a side elevation of a combination lock and time mechanism embodying the invention;

Figure 2 is a sectional elevation through a safe or vault, looking at the inner face of the door thereof, upon which is shown one embodiment of the invention in connection with the bolt-work for locking the door;

Figure 3 is a rear elevational view of the combination lock and time-mechanism showing the parts in locking position, and

Figure 4 is a similar view with the bolt-work obstructing means in release position.

Similar reference numerals throughout the several views indicate the same parts.

The present invention is designed to afford a safe guard, particularly against daylight holdups of bank vaults and the like by holding in check the bolt-work for locking the door of the vault for a predetermined length of time after the combination has been released, whereby to foil any attempt of bandits or bank robbers in gaining immediate access to the contents of the vault upon entering the bank.

In the present embodiment of the invention 10 represents conventionally a safe or vault having a door or closure 11 provided on its inner face with rearwardly projecting ribs or plates 12 in which are slidably mounted the bolts 13 shown in locking position in Figure 2. The bolts are connected by a vertically disposed bar 14 which is adapted to actuate the bolts simultaneously, the bar being moved by any suitable means such as the handle 15 and crank arm 16 having its free end disposed between the lugs 18 of the bar as shown in Figure 2. The bar is provided with a laterally extending rod or projection

19 in the path of which is normally disposed a suitable guard or obstructing device 20 preferably pivotally mounted within a casing 21 secured on the back of the door 11 and containing the time-mechanism, the casing having a door 22 hinged thereon which is provided with a transparent panel 23 through which the time-mechanism is rendered visible. The casing is spaced slightly from the door 22 preferably by a plurality of rubber or other yieldable spacing members 24 as shown in Figure 1, which affords a certain degree of protection to the time-mechanism by partially absorbing the blows to which the door 11 may be subjected from time to time.

The combination lock casing, indicated at 25, is disclosed upon the rear face of the safe door slightly above the time-mechanism casing 21 and is provided with a cover 26 shown removed in Figure 4. The usual knob and dial plate for the combination lock are indicated at 27 and 28, respectively. The combination lock may be of any particular construction desired and if preferred may be included in a casing containing the time-mechanism. The present combination lock, of a well known type, is illustrated in release position in Figure 4 and includes the usual tumblers 29 and disk 30 rigid on the tumbler shaft 31. The disk is provided with a cam surface 32 for raising the pivoted locking dog and operating connection 33 to destroy the combination during rotation of the disk in a clockwise direction as viewed in Figure 4. The operating member 34 for raising the guard 20 is moved to the right from the position shown in Figure 4 through rotation of a lug 35 on the disk in engagement with an arm 36 of the operating member 34, the latter being returned to the position shown in said figure through engagement of the lug 35 with a shoulder 37 of the connection 33.

The operating member 34 includes an offset portion 38 and a depending arm or lever 39 which projects through a slot 40 in the bottom of the casing 25. The arm 39 is projected between the door 11 and the time-mechanism casing 21 as best shown in Figure 1 and is provided at its lower end with an angular portion 41 which carries an upstanding portion 42 projected through a slot 43 in the bottom of the casing 21 and into a recess 44 formed in the guard 20. The upstanding portion is provided with a curved or inclined surface 45 adapted to engage an inclined surface 46 on the guard to raise the latter to the position shown in Figure 3 when the arm 39 is moved by the combination lock upon destroying the combination with the bolt-work in position to lock the door as shown in Figure 2. The guard 20 is thus brought to a position in which it will lie directly in the path of the rod 19 opposite the opening 47 in the casing 21 through which the rod is adapted to project when the guard

has been released by the timing-mechanism and dropped by gravity to the position shown in Figure 4. The guard or obstructing member 20 is suitably pivoted at 48 within the casing 21 with its free end resting upon the bottom of the casing when in release position.

The timing-devices, two of which are shown, may constitute any suitable mechanism for releasing the guard 20, but are so controlled by the combination lock as to remain inactive until the combination is released, at which time they begin to operate. They are preferably so designed as not to run down before releasing the guard 20, being shown in run down position in Figure 4. The timing-devices operate independently of each other and anyone of them will effect release of said guard 20. The casing 21 is preferably designed to hold three of the timing-devices, but only two are shown, it being understood that more than one is provided as a matter of safety so that should one become disabled the other will function for the purpose provided. Each timing-device comprises a rotatable dial 49 having 90 graduations 50 representing any divisions of time desired, such, for example, as hours shown in the present instance as divided into 15 minute periods. A fixed pointer or index member 51 is arranged to correspond to the zero position of the dial when the latter is in rundown position. Previous to closing and locking the safe or vault the dials are set for a predetermined period, determined by the official in charge, being shown set in Figure 3 for a period of one hour, merely by way of example. The setting is effected through the medium of a suitable key adapted to be inserted upon the motor driven arbor 52 for winding the mechanism, the usual train of gears being provided as shown for driving the dials, which are adapted to rotate counterclockwise as viewed in Figure 3. The usual escapement wheel is indicated at 53 and the pallet for controlling the same is shown at 54.

Immediately upon closing the door and destroying the combination the depending arm 39 is moved from the position shown in Figure 4 to that shown in Figure 3 to move the guard 20 into obstructing position. The arm carries with it a rod 55 slidably mounted in a bracket 56, said rod having depending fingers 57 which are moved into engagement with the pallets 54 to prevent oscillation of the same whereby operation of the timing-devices is also prevented as long as the combination lock remains unreleased.

The means for holding the guard in obstructing position comprises a latch member 58 having a tongue or shoulder 59 adapted to project under a laterally extending pin 60 of the guard as shown in Figure 3. The latch member is dependably supported by a slidably mounted bar 61 which is supported by a

pair of pins or screws 62 and 63 adapted to project respectively through slots 64 and 65 at the ends of the bars, the screws being carried by the inwardly projecting lugs 66 of the 5 casing 21 as shown in Figure 4. The bar 61 is provided with upstanding arms or projections 67 disposed in the path of the laterally projecting pins 68 carried by and adapted to rotate with the dial wheels. The latch 58 10 is normally held in position to support the guard 20 by means of a spring 69 after the timing-devices have been set, as indicated in Figure 3. The spring is preferably disposed within a housing 70 suitably secured upon the 15 bar 61, the outer end of the spring engaging a plunger rod 71 which is guided by the housing and which is held against outward movement by one of the end walls of the casing 21 as shown in Figure 4. The plunger rod is 20 provided with a reduced portion 72 projecting through said wall which serves to hold the bar in proper alignment during operation. Rotation of the pins 68 with the dial wheels in a counter-clockwise direction, as viewed in 25 Figure 3, will cause the same to engage the arms 67 of the latch bar when the timing-devices are nearing rundown position and as they continue to operate the latch 58 is gradually withdrawn from beneath the pin 60 of 30 the guard 20 to release the latter, at which time it will drop by gravity to the position shown in Figure 4 and permit movement of the bolt work to unlocking position.

Upon raising the guard 20 through movement of the arm 39 the pin 60 will ride upon the inclined surface 73 of the latch 58 and move the latter to the right against the action of the spring 69, the latch being snapped into position beneath said pin by the spring 40 when the guard has been raised to a predetermined height. The pin 60 at a point opposite the latch is preferably provided with a V-shaped portion 74 to facilitate cooperation between the pin and latch in the holding and 45 releasing of the guard.

While I preferably employ a combination lock for controlling the timing-mechanism it will be understood that other types of locks may be used for the same purpose, such as a 50 key lock, and I do not therefore wish to limit the invention to any particular form of lock for control of or cooperation with the timing-mechanism.

I claim as my invention:

1. In combination, a safe or vault including a closure and securing mechanism therefor, a lock, timing-mechanism, means movable to and from obstructing position with relation to said securing mechanism, and devices controlled by said lock and timing-mechanism, one of which is effective to move said means to obstructing position and the other to release the same after operation of the timing-mechanism for a predetermined period.
2. In combination, a safe or vault including a closure and securing mechanism therefor, a lock, timing-mechanism, means movable to and from obstructing position with relation to said securing mechanism, devices controlled by said lock and timing-mechanism, one of which is effective to move said means to obstructing position and the other to release the same, and means controlled by the lock for preventing operation of the timing-mechanism previous to movement of the lock to release position. 70
3. In combination, a safe or vault including a closure and bolt-work therefor, a combination lock, timing-mechanism, means movable to and from obstructing position with relation to said bolt-work, devices for moving said means to obstructing position and for releasing the same, one of which is operatively connected with the combination lock 80 and the other with the timing-mechanism and means controlled by the device for moving said means to obstructing position adapted to prevent operation of the timing-mechanism previous to release of the combination. 85
4. The combination with a timing-mechanism, a combination lock and a releasable obstructing device for the securing mechanism of a closure, of means controlled by the combination lock for moving the obstructing device to operative position upon destroying the combination, and means controlled by the timing-mechanism for releasing the obstructing device after operation of the timing-mechanism for a predetermined period. 90
5. The combination with a timing-mechanism, a combination lock and a releasable obstructing device for the securing mechanism of a closure, of means controlled by the combination lock for moving the obstructing device to operative position upon destroying the combination, means adapted to prevent operation of the timing-mechanism while the combination lock is in locking position, and means controlled by the timing-mechanism 100 for releasing the obstructing device at a predetermined time. 105
6. The combination with a timing mechanism, a combination lock and a releasable obstructing device for the securing mechanism of a closure, of means controlled by the combination lock adapted to move the obstructing device to operative position and to prevent operation of the timing-mechanism while the combination lock is in locking position, and means controlled by the timing-mechanism for releasing the obstructing device subsequent to a predetermined period of operation of the timing-mechanism. 115
7. In combination, a safe or vault including a closure and securing mechanism therefor, a combination lock, timing mechanism, a member movable to and from obstructing position with relation to said securing mechanism, a device operatively connected with the 120
- 130

combination lock for moving said member to obstructing position and a latch for normally holding the obstructing member in operative position adapted to be released by the timing-mechanism after operation of the same for a predetermined period.

8. In combination, a safe or vault including a closure and securing mechanism therefor, a lock, timing-mechanism, means movable to and from obstructing position with relation to said securing mechanism, devices adapted to be simultaneously moved by the lock upon operation of the same to both prevent operation of the timing-mechanism and to move said means to obstructing position, and means operated by the timing-mechanism subsequent to the release of the lock for releasing the obstructing means.

9. In combination, a safe or vault including a closure and bolt-work for securing the latter, a device movable to and from obstructing position with relation to the bolt-work, a lock, timing-mechanism, parts connected with the lock and adapted to be actuated thereby, one of which is adapted to move said device to obstructing position and another to engage a controlling part of the timing-mechanism to prevent operation thereof previous to release of the lock, said parts being moved to release position upon releasing the lock, and means controlled by the timing-mechanism for releasing the obstructing device after the timing-mechanism has been operated for a predetermined period.

10. In combination, a safe or vault including a closure and securing means therefor, a device movable to and from obstructing position with relation to the securing means, a lock, timing-mechanism, an arm connected with the lock adapted to move said device to obstructing position upon movement of the lock to locking position, a member connected with the arm adapted during operation thereof to move into obstructing position with relation to the controlling portion of the timing-mechanism to prevent operation thereof previous to release of the lock, and a latch adapted to hold the obstructing device in obstructing position and arranged to be released by the timing-mechanism after it has operated for a predetermined length of time.

11. In combination, a safe or vault including a closure and bolt-work for securing the latter, a member adapted to be raised into obstructing position with relation to the bolt-work, a latch for holding said member in obstructing position, a lock, timing-mechanism including a driven member having a projecting portion rotatable therewith to effect release of the latch after operation of the timing-mechanism for a predetermined period, a device connected with the lock for raising said member to obstructing position upon moving the lock to locking position,

and means connected with said device for obstructing a controlling portion of the timing-mechanism to prevent operation thereof previous to release of the lock, said obstructing member being adapted to drop by gravity when released by the timing-mechanism.

12. In combination, a container including a closure, securing mechanism therefor including relatively movable parts one of which forms a guard for another, a releasable holding device for the guard, power means for releasing the holding device operable for a predetermined period previous to effecting its release and a lock for the closure having means normally holding said power means in check and adapted to effect release of the same and also including means adapted to place the guard in protecting position when moved to guard the power means.

13. In combination, a container including a closure, securing mechanism therefor including relatively movable parts one of which forms a guard for another, a releasable holding device for the guard, power driven releasing means for the holding device operable for a predetermined period previous to effecting release of said holding device and a combination lock having an arm movable to position the guard in protecting position, and means operated by the arm for normally holding said power driven means against operation.

14. In combination, a container including a closure, securing mechanism for the closure including bolt work and a releasable guard therefor, control means including a driven member adapted after operation for a predetermined period to effect release of said guard, a member operable from the exterior of the container and means adapted to be actuated thereby including parts arranged to both move the guard from release position into obstructing position with relation to the bolt work and to obstruct the control means whereby to hold it in check for any desired period.

15. In combination, a container, including a closure, securing mechanism for the closure, releasable guard means therefor, timing mechanism adapted after operation for a predetermined period to effect release of the guard means, a combination lock for the closure, parts arranged to be moved by the lock when the combination is destroyed, one being adapted to move the guard from release to obstructing position and another serving to obstruct the timing mechanism whereby to hold it in check for a definite period.

16. In combination, a container including a door, releasable securing means therefor, guard means mounted independently of the securing means for obstructing the latter, timing mechanism for effecting release of the guard means after operation for a predetermined period, a member arranged for

operation from the exterior of the container and means under the control of said member mounted independently of the timing mechanism and including parts, one of which is adapted when the door is closed to reset the guard means in obstructing position and another to obstruct the timing mechanism to prevent operation thereof.

17. In combination, a container including a closure, timing mechanism carried thereby, a guard movable to and from a predetermined position, releasable means for holding the guard in said position adapted to be actuated by the timing mechanism after operation thereof for a predetermined period whereby to effect release of the guard, securing mechanism for the closure mounted independently of the guard and adapted when in securing position to be obstructed by the guard when the latter is in said predetermined position and means controllable from the exterior of the container when the closure is in closed position to both obstruct the timing mechanism to prevent operation thereof and to move the guard to said predetermined position.

18. In combination, a container including a closure, releasable securing means therefor including a part movable therewith in a predetermined path, a pivoted guard adapted to swing into said path in position to obstruct said part when the securing means is in locking position, holding means for securing the guard in obstructing position, timing mechanism for effecting release of said holding means, an operating member disposed exteriorly of the container and devices adapted when the securing mechanism is in locking position to be moved by the operating member, one to move the guard into obstructing position for support by the holding means and the other into position to prevent operation of the timing mechanism.

19. In combination, a container including a closure, securing means for the closure, releasable guard means therefor including a member movable to and from obstructing position with respect to the securing means and also including a spring pressed holder for said member, timing mechanism adapted after operation for a predetermined period to move said holder whereby to effect release of said obstructing means, a member operable from the exterior of the container and parts arranged to be actuated thereby with the closure in closing position, one being adapted to move the guard into position to be supported by the spring pressed holder and another serving to obstruct the timing mechanism whereby to hold it in check for a definite period.

20. A locking mechanism for safes and the like having bolt work for securing the door of the safe comprising releasable guard means for the bolt work mounted for operation in-

dependently thereof, a timing mechanism including an operating part for releasing the guard means normally occupying a position in spaced relation thereto and arranged after operation of the timing mechanism for a predetermined period to move into position to release the guard means and a combination lock mechanism having a member under the control thereof for moving the guard means to securing position when the combination is destroyed and having means for holding the timing mechanism in check when the operating part for the guard means is in the first mentioned position, said member being arranged to release said timing mechanism upon successively operating the combination mechanism.

21. In a locking mechanism for safes and the like, releasable guard means for the bolt work of the safe, control means operable from the exterior of the safe when closed serving to effect movement of said guard means whereby to hold the bolt work against release, timing mechanism arranged after operation for a predetermined period to release said guard means, and means for holding said timing mechanism in check, said means being spaced from and independent of the guard means in all positions thereof and arranged to be released by operation of said control means.

22. In a locking mechanism for safes and the like, releasable guard means for the bolt work of the safe, control means operable from the exterior of the safe when closed serving to move said guard means into position to hold the bolt work against release, timing mechanism arranged after operation for a predetermined period to release said guard means, and means spaced from and independent of the guard means arranged to be operated by the control means to and from position to hold said timing mechanism in check.

23. In a locking mechanism for safes and the like, releasable guard means for the bolt work of the safe, timing mechanism arranged after operation for a predetermined period to release said guard means, a combination lock mechanism, and parts under the control of said last mentioned mechanism one of which is arranged upon destroying the combination when the safe is closed to position the guard means for holding the bolt work against release and another serving to hold the timing mechanism in check, said timing mechanism being freed for operation upon successfully operating the combination and serving to subsequently release said guard means.

24. The combination of a safe having a door, bolt work for securing the door, guard means for the bolt work operable independently thereof, a timing mechanism arranged after operation for a predetermined period

- to effect release of the guard means, a combination lock mechanism, means spaced from and independent of the guard means for holding the timing mechanism in check arranged to be released by said last mentioned mechanism upon successfully operating the combination, means actuated by said combination lock mechanism upon destroying the combination arranged to move the guard means into position to secure the bolt work and means for releasing the bolt work after operation of the guard means by the timing mechanism.
25. The combination of a safe having a door, bolt work for securing the door, guard means for the bolt work operable to hold the same against release, a combination lock mechanism, timing mechanism arranged after operation for a predetermined period to release said guard means and means under the control of the combination lock mechanism including a part spaced from and independent of the guard means arranged upon destroying the combination to move into position to hold the timing mechanism in check, and means actuated by the combination lock mechanism when moved to locking position operating to move the guard means into position to secure the bolt work.
30. 26. In combination, means for protecting a securing device comprising a timing mechanism, a lock, guard means for said securing device and parts under the control of the lock one of which is arranged when the lock is moved to locking position to move the guard means to protecting position with respect to said securing device and another operating to hold the timing mechanism in check, said last mentioned part being released by the lock 35 when the latter is moved to unlocked position.
27. In a locking mechanism for safes and the like provided with securing means, releasable guard means for the securing means comprising relatively movable cooperating parts, control means arranged to be operated from the exterior of the safe when closed and serving to move one of said parts into cooperating relation with another to protect 40 the securing means, timing mechanism having a part arranged after operation of the mechanism for a predetermined period to move into position to engage and release one of said cooperating parts to effect release of 45 the securing means, and means for holding said timing mechanism in check arranged to be released by movement of said control means to a predetermined position.

HERBERT F. WALKER.
